UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,251,142.

Specification of Letters Patent. Patented Dec. 25, 1917.

Application filed April 26, 1915. Serial No. 23,864.

To all whom it may concern:

Be it known that I, JESSE G. VINCENT, a citizen of the United States, and resident of Detroit, Wayne county, State of Michigan, have invented certain new and useful Improvements in Hydrocarbon-Motors, of which the following is a specification.

This invention relates to multi-cylinder hydrocarbon motors, and particularly to the 10 construction and arrangement of cylinder blocks, valve mechanism, carbureters, intake and exhaust passages, etc.

One of the objects of the invention is the construction of a multi-cylinder V motor 15 so that the valves are accessible for adjustment and for grinding, so that the intake and exhaust passages are conveniently and advantageously arranged relative to the valves and to each other, and so that a single 20 carbureter may be connected to the intake passages of the motor with as little exposed piping as possible.

Other objects of the invention will appear 25 from the following description taken in connection with the drawings which form a part of this specification and in which:—

Figure 1 is a plan view of a hydrocarbon motor made in accordance with this invention;

Fig. 2 is a vertical section approximately 30 on the line 2—2 of Fig. 1; and

Fig. 3 is a side elevation of the motor shown in the other figures.

The invention is illustrated herein in connection with a twelve cylinder motor in which the cylinders are arranged in two blocks of six cylinders each and positioned on the crank case in V relation. Some of the features of the invention are applicable 40 to motors having a lesser number of cylinders or to other arrangements thereof.

Referring to the drawing, 10 represents generally the motor base or crank case comprising principally an upper half 11 and a lower half or oil well 12. Upon the crank case are mounted the cylinder blocks or castings 13, two of such blocks being shown and the blocks being arranged in V position on the crank case. In the twelve cylinder motor shown the cylinders are positioned at an angle of 60 degrees; in an eight cylinder motor the angle would probably be 90 degrees.

It will be observed that these cylinder blocks or castings are suitably water jack-

eted as at 14, and are provided with water inlet pipes 15 and outlet pipes 16.

Each of the cylinders is provided with the usual piston 17, and a connecting rod 18 connects the piston in driving relation with the crank shaft 19 mounted in suitable bearings 20 in the crank case 10.

Inlet and exhaust ports 21 and 22 respectively, are formed in the cylinder blocks in series along the outer sides of the blocks. 65 One of the intake ports 21 is shown in Fig. 2 at the left side of the drawing, and one of the exhaust ports 22 is shown at the right hand side thereof. These ports of course communicate with the combustion space 23 of the cylinders and they are arranged substantially horizontally with a cap 24 screwed into the cylinder casting immediately above each of the ports, to thus make the ports accessible for grinding and inserting the valves hereinafter described. Spark plugs 24' may be arranged in these caps 70 over the intake valves or otherwise as desired.

Referring particularly to Fig. 2 it will 80 be observed that the intake valves 25 and exhaust valves 26 are herein shown as of the poppet variety and are arranged substantially vertically and in series along the outer edges of the cylinder blocks where 85 they and their connections are most accessible. These valves of course control the intake and exhaust ports 21 and 22 and are provided with suitable springs 27 and push rods 28 beneath their stems. The push rods 90 28 are mounted in sleeves 29 in extensions of the crank case 10, and are reciprocated for the purpose of opening the valves 25 and 26 by means of suitable cams 30 on cam shafts 31 arranged longitudinally of the motor and at the sides of the crank shaft 19. These cam shafts 31 are operated from the crank shaft 19 through any suitable gearing such as the gear 32 on the crank shaft, the gears 33 on the cam shafts, and the idler 100 gears 34. These gears are shown diagrammatically in Fig. 2.

A particularly advantageous arrangement of intake and exhaust conduits or passages is shown in the form of the invention here- 105 illustrated. The intake ports 21, of which there are of course six for each cylinder block, are fed by a conduit or passage 35 which extends longitudinally of each of the cylinder blocks adjacent their outer 110

edges, or as shown particularly in Fig. 2 these conduits 35 are arranged between the cylinders proper and the valves. In the drawings these conduits 35 are shown formed as an integral part of the cylinder casting. This arrangement provides sufficient heat for the intake gases to prevent condensation, and thereby promotes uniform firing of the cylinders.

10 The exhaust ports 22, of which there are also six for each of the cylinder blocks, are connected to exhaust conduits or passages 36 which are also arranged longitudinally of the cylinder blocks and along their outer edges. As shown, these conduits 36 are formed separately and are secured to the cylinder blocks as by the bolts 37. It will be seen that the exhaust conduits are arranged parallel to the intake conduit 35, but 20 are outside of the valves.

The motor carbureter 38 is arranged between the cylinder blocks and is provided with a short pipe connection 39 which connects the carbureter with conduits 40 which 25 lead to the intake conduits or passages 35 of the two cylinder blocks. These conduits 40 are indicated in dotted lines in Fig. 2 and are preferably formed as an integral part of the castings. The conduits 40 pass between 30 two of the cylinders in carrying the gases from one side of the cylinder blocks to the other.

Other forms of the invention will readily suggest themselves to one skilled in the art, 35 and the claims are understood as not limited to the exact form of the invention shown herein.

Having thus described my invention, what I claim and desire to secure by Letters Patent is:—

1. In a multi-cylinder hydrocarbon motor, the combination of a cylinder block having cylinder bores and valve seats, valves for said seats, the axes of the valves and cylinder bores being at acute angles to each other, a gas conduit extending longitudinally of the cylinder block and arranged between the valves and the cylinder bores, and means for operating the valves.
2. In a multi-cylinder hydrocarbon motor, the combination of a cylinder block having cylinder bores and valve seats, valves for said seats, the axes of the valves and cylinder bores being at acute angles to each other, intake and exhaust conduits extend-

ing longitudinally of the cylinder block and arranged on opposite sides of said valves, and means for operating said valves.

3. In a multi-cylinder hydrocarbon motor, the combination of a cylinder block 60 having cylinder bores and valve seats, valves for said seats, the axes of the valves and cylinder bores being at acute angles to each other, an intake conduit arranged between the valves and the cylinder bores, a carbureter on the side of the block opposite to the valves, and a conduit extending through the block from the carbureter to said intake conduit.

4. In a multi-cylinder hydrocarbon motor, the combination of a crank case, cylinder blocks arranged in V position thereon, intake conduits on the outside of said blocks, a carbureter between the cylinder blocks, and conduits connecting the carbureter and 75 intake conduits.

5. In a multi-cylinder hydrocarbon motor, the combination of a crank case, cylinder blocks arranged in V position thereon, intake conduits on the outside of said blocks, 80 a carbureter between the cylinder blocks, and conduits passing through the cylinder blocks and connecting the carbureter and intake conduits.

6. In a multi-cylinder hydrocarbon motor, the combination of a crank case, cylinder blocks arranged in V position thereon, and having intake ports along their outer edges, a carbureter arranged between the cylinder blocks, and conduits leading from 90 the carbureter to the respective intake ports.

7. In a multi-cylinder hydrocarbon motor, the combination of a crank case, cylinder blocks arranged in V position thereon and having integral intake passages cast 95 along their outer sides and having intake ports communicating with said passages, a carbureter arranged between said cylinder blocks, conduits connecting said carbureter with said intake passages, vertically arranged valves for said ports, cam shafts for operating said valves, and means for driving said cam shafts.

In testimony whereof I affix my signature in the presence of two witnesses.

JESSE G. VINCENT.
